UNITED STATES PATENT OFFICE.

ARCHIE E. PARNALL, OF CHICAGO, ILLINOIS.

DESIGN FOR A TALKING-MACHINE CABINET.

• 50,139.

Specification for Design.

Patented Jan. 2, 1917.

Application filed September 18, 1916. Serial No. 120,908. Term of patent 3½ years.

To all whom it may concern:

Be it known that I, ARCHIE E. PARNALL, a citizen of the United States, residing at Chicago, in the county of Cook and State of Illinois, have invented a new and original and ornamental Design for a Talking-Machine Cabinet, of which the following is a specification, reference being had to

the accompanying drawing, forming a part thereof.

The figure is a perspective view of a talking machine cabinet showing my new design.

I claim:

The ornamental design for talking machine cabinet as shown.

ARCHIE E. PARNALL.
